DUPLEX ELECTRICAL ADAPTER

Ernest R. Carlson, Fairfield, Conn., assignor to Harvey Hubbell, Incorporated, Bridgeport, Conn., a corporation of Connecticut

Filed Aug. 21, 1962, Ser. No. 71,400

Term of patent 14 years

(Cl. D26—1)

FIG. 1 is a front perspective view of a duplex electrical adapter showing my new design;

FIG. 2 is a rear perspective view thereof;

FIG. 3 is a front elevational view thereof;

FIG. 4 is a side elevational view thereof;

FIG. 5 is an end elevational view thereof, the opposite end being substantially a mirror image thereof, and

FIG. 6 is a fragmentary cross-sectional view taken on line 6—6 of FIG. 3 on an enlarged scale.

The dominant features of my new design are shown

in solid lines in the drawing and reside primarily in the raised portions on the face of the adapter as shown.

I claim:

The ornamental design for a duplex electrical adapter, substantially as shown and described.
